FRANK E. BAKER, OF SYRACUSE, NEW YORK, ASSIGNOR OF ONE-HALF TO LOUIS WILL, OF SYRACUSE, NEW YORK

IRONING PRESS

Application filed September 9, 1930. Serial No. 480,629.

This invention relates to an ironing press of the class set forth in my pending applications Serial No. 367,380, filed May 31, 1929 and Serial No. 436,534, filed March 17, 1930, except that the press head is mounted upon a wheel carriage adapted to be rolled upon a table or other horizontal supporting surface and that the buck is loosely mounted upon the same horizontal surface in a plane between the lower and upper arms and in front of the closed side of the U-shaped carriage and is provided with cushion feet resting upon said surface for frictionally holding the buck against accidental sliding movement on said surface during the ironing operation.

The main object is to provide a simple and highly efficient ironing press of this character in which the buck support and head support are made in separate portable units capable of being easily and quickly placed, one at a time, in operative position upon the surface of a table or other horizontal support ready for use and as quickly and easily removed and stored away when the ironing operations are completed, thus leaving the table free to use for other purposes.

One of the specific objects is to provide the buck-supporting frame with cushion feet adapted to rest upon the supporting surface for frictionally holding the same against accidental sliding movement upon said surface and at the same time reducing to a minimum any liability of marring said surface.

Another specific object is to provide the head supporting carriage with supporting wheels resting upon said surface to permit the carriage to be rolled forwardly and rearwardly for effecting a corresponding movement of the press head to and from a position directly over the buck and at the same time to yieldingly support the press head upon the carriage for independent vertical movement to and from its pressing position.

In my pending applications, above referred to, the carriage is movable along and upon a track which in turn is secured to a horizontal support and one of the broad objects of the present invention is to reduce to a minimum the number of parts required for the success-

ful operation of a machine of this character by causing the head supporting carriage and buck supporting frame to loosely rest upon any available horizontal supporting surface such as a table which, when these units are removed, may be used for other purposes, thus permitting the entire ironing press to be made and sold at an extremely low cost to the user.

In fact, in some instances where a built-in ironing board is employed and adjusted for use, the buck and its supporting frame herein illustrated could be dispensed with in which case an ordinary kitchen table or equivalent support might be placed in a position directly under the ironing board for receiving and supporting the head-supporting carriage without departing from the spirit of the present invention, thereby further reducing the number of parts and cost of installation of the ironing press.

Other objects and uses relating to specific parts of the machine will be brought out in the following description.

In the drawings:

Figure 1 is a top plan and Figure 2 a front elevation of an ironing press embodying the various features of my invention as used in connection with an ordinary kitchen table or equivalent support having a substantially horizontal upper surface.

Figure 3 is an enlarged end view, partly in section, of the same machine, the press head and its depressing means being shown by full lines in their forward positions while the portion of the carriage and its press head is shown by dotted lines in its rearmost position leaving a clear open space entirely around the marginal edges of the buck for the reception and proper arrangement of the garment thereon preparatory to ironing.

Figure 4 is a horizontal sectional view taken in the plane of line 4-4, Figure 3.

Figure 5 is an enlarged detail horizontal sectional view taken in the plane of line 5-5, Figure 2.

Figure 6 is an enlarged detail vertical sectional view taken in the plane of line 6-6, Figure 2.

Figure 7 is an enlarged detail vertical sec-

100

tional view taken in the plane of line 7—7, Figure 3.

Figure 8 is a detail vertical sectional view taken in the plane of line 8—8, Figure 5.

As illustrated this machine comprises a portable buck supporting frame —1— carrying a buck —2— and constituting what may be termed a garment supporting unit, and a portable head supporting frame —3— carrying a press head —4— which, together with the frame —3— and connections between the press head and said frame, constitute what may be termed the pressing unit, each unit being made separately from the other and constructed in such manner that it may be easily handled and transported from one place to another for installation upon any horizontal surface as, for example, upon the surface of a table —A— or may be separately stored in compact space in any available place to allow the table to be used for other purposes.

The pressing surface of the buck —2— and press head —4— are usually of equal area and are preferably elongated laterally a distance several times their width so as to afford a relatively large pressing area upon a garment in one and the same operation, thereby greatly reducing the time required for ironing sheets, tablecloths, and other articles of larger area than the surface of the pressing elements.

In many instances, however, these larger articles may be folded in such manner that they may be satisfactorily ironed in one operation.

The press head is preferably hollow to receive a suitable heater, preferably an electric heater of the class set forth in my pending application Serial No. 400,652, filed October 18, 1929, while the buck —2— is preferably unheated except for such heat as may be transmitted thereto from the head, it being understood that the articles to be ironed are usually brought to the machine in a more or less damped condition commonly practiced in laundry work.

The buck —2— comprises a sheet metal plate —5— and a pad —6— mounted thereon to form a yielding support for the articles to be ironed, the plate —5— being provided with a downturned marginal flange —7— for reinforcing purposes, thus permitting the plate to be made of comparatively thin sheet metal for reducing the weight thereof.

The plate —5— is mounted directly upon the top of its supporting frame —1— having all parts thereof a considerable distance within the marginal edges of the buck to leave a clear open space around and under said marginal edges and thus permit the articles to be ironed to be properly manipulated or spread out upon the upper surface and around said marginal edges preparatory to ironing the same, it being understood that

the operator will stand at one side of the buck substantially midway between the ends thereof for convenience of operation of the garment and press head from one and the same position, commonly known as the front side of the machine.

The buck-supporting frame may be of any desired construction but preferably comprises a pair of forwardly and rearwardly extending angle irons —8— arranged in parallel spaced relation in a substantially horizontal plane and supported upon suitable legs —9— having cushioned feet —10— of relatively soft rubber or equivalent material adapted to loosely rest directly upon the upper surface of the table —A— to frictionally hold the buck-supporting frame against accidental lateral movement upon the table surface.

These angle irons are arranged with their angles facing outwardly so that their inner flanges may project downwardly from the inner edges of the upper horizontal flanges at the inner sides of the adjacent legs —9— to form guides between which the lower portion of the head supporting carriage is movable in a manner herein more fully explained, the upper horizontal flanges of the angle irons —8— being spot-welded or otherwise permanently secured to the upper ends of the legs —9— which extend downwardly some distance below the lower edges of the angle irons to support said angle irons some distance above the surface of the table when the buck supporting frame is placed thereon.

A pair of lengthwise bars —11— are spot-welded or otherwise secured to the upper faces of the transverse bars —8— in transversely spaced parallel relation as shown more clearly in Figures 2 and 3 for holding said bars —8— in fixed relation, said lengthwise bars —11— preferably consisting of angle irons arranged with their open sides facing each other and their lower flanges secured directly to the upper faces of the transverse bars —8—, and, together with said transverse bars and legs —9—, constitute what may be termed the base frame of the buck-supporting frame.

A plurality of, in this instance four, upright posts —12— are spot-welded or otherwise secured at their lower ends to the horizontal flanges of the lengthwise bars —11— to extend upwardly equal distances therefrom in uniformly spaced relation transversely and also in uniformly spaced relation longitudinally of the machine as shown more clearly in Figures 2 and 3.

A pair of transverse bars —13— are spot-welded or otherwise secured to the upper ends of the posts —12— in longitudinally spaced parallel relation for receiving and supporting a pair of lengthwise bars or angle irons —14— which are spot-welded or otherwise secured to opposite ends of the transversely

130

extending bars —13— in transversely spaced parallel relation and in a plane some distance above but parallel with the lower lengthwise bars —11— as shown in Figure 3.

5 These bars —13— and —14— constitute what may be termed the upper frame of the main supporting frame and serve to receive and support the buck —2— having its metal plate —5— spot-welded or otherwise secured to the upper faces of the angle iron bars —14—, the posts —12— serving as connections between the lower and upper supplemental frames of the main supporting frame for the buck.

10 15 It is now clear that the buck-supporting frame as a unit is of a skeleton type to assist in reducing the weight of the machine and particularly the buck-supporting unit.

20 *Head supporting unit*

The head supporting unit comprises a pair of similar U-shaped frame members —15— arranged edgewise vertically in longitudinally spaced parallel planes with their open 25 sides facing forwardly or toward the front of the machine to form what may be termed the U-shaped carriage —3— having its lower and upper arms substantially parallel and disposed respectively in planes some distance 30 below and also some distance above the plane of the buck —2— to extend transversely thereof.

The transverse lengths of the lower and 35 upper arms of the carriage —3— are considerably greater than the transverse width of the buck —2— so that when the carriage is brought forwardly to its pressing position the rear closed sides of the U-shaped members —15— will be spaced some distance from the 40 rear edge of the buck to allow the articles to be ironed to pass freely through the intervening space when necessary, without in any way interfering with the free backward and forward movement of the carriage, in a manner presently described.

The lower arms of the U-shaped members —15— are connected by lengthwise shafts —16— arranged in transversely spaced parallel relation and having their opposite ends 50 journaled in suitable bearings in the lower arms as shown more clearly in Figure 4, said shafts being provided with tight collars —16'— on opposite ends thereof adjacent the outer faces of the lower arms of the members —15— to hold said shaft against undue endwise movement in their respective bearings.

Each shaft is provided with a pair of supporting wheels —17— adjacent the inner 60 faces of the lower arms of the members —15— and adapted to roll upon the upper surface of the table —A— and thus permit the carriage —3— to be moved freely forwardly and rearwardly for effecting a corresponding

movement of the press head —4— to and from a position above the buck —2—.

The lengths of the shafts —16— are approximately equal to or slightly less than the distance between the lower transverse frame bars —8— which serve as guide members to direct the forward and rearward movements of the carriage in a rectilinear path parallel with the frame members —8—.

The lower arms as —15'— of the carriage as —16— of the carriage are of slightly less vertical width than the distance between the lower faces of the lengthwise frame bars —11— and lower ends of the cushioned feet —10— so that when the buck-supporting frame is resting upon the upper surface of the table —A— the lower arms of the carriage may move freely through the intervening space between said surface and lower faces of the bars —11— and still be held against vertical movement during the pressing operation.

The diameters of the carriage-supporting wheels —17— are also slightly less than the vertical distance between the table surface and lower faces of the bars —11— to allow them to move freely through the intervening space without frictional engagement with said bars as shown more clearly in Figures 2 and 3.

The frontends of the upper arms as —15"— of the U-shaped members —15— are connected by a longitudinally extending handle bar —18— having its opposite ends secured in suitable openings in the arms —15"— to hold the latter in fixed relation against undue lateral movement.

These U-shaped bars —15— are preferably made of flat steel or equivalent more or less resilient material arranged edgewise vertically so as to afford considerable spring resistance against relative vertical movement of the free ends thereof and at the same time to exert considerable pressure on the press head toward the buck when the press head is moved into engagement with the buck in a manner presently described for effecting the desired ironing pressure upon the articles on the buck.

115 *Spring suspension for the head*

Suitable means is provided for yieldingly holding the press head —4— in a plane some distance above the upper surface of the buck to afford ample clearance for the articles to be ironed between the buck and head as the latter is moved to and from a position above the buck and at the same time to allow the head to be forced into pressing co-action with the buck when registered therewith as shown by full lines in Figure 3.

120 For this latter purpose I have provided a pair of flat leaf springs —19— each located adjacent the outer face of one of the U-shaped arms —15— as shown more clearly in Figure 1, and having their rear ends returned in

wardly and outwardly at —19— and secured to suitable anchor bolts —20— on the adjacent portions of the arms —15— as shown more clearly in Figures 3 and 7.

6 These anchor bolts are located near the rear end of the carriage so that the springs extend forwardly therefrom in planes above the head —4—, the front ends of the springs being pivotally connected at —21— to suitable lugs —22— which are bolted or otherwise secured at —23— to the upper surface of the press head —4— so that the pivotal connection —21— will be approximately midway between the front and rear edges of the head 10 as shown in Figures 1 and 3, said anchor bolts being passed through apertures in their respective arms —15— and tightly clamped in place but may be adjusted angularly about their respective axes for placing the springs 15 under sufficient tension to yieldingly support the head above and in spaced relation to the buck.

15 It is now clear that the press head —4— is pivotally suspended from the front ends of the spring —19— which constitute a resilient connection between the carriage —3— and press head —4— and that the press head may move backwardly and forwardly with the carriage to and from a position directly over 20 the buck as shown by full lines in Figure 3, or to and from a position some distance to the rear of the buck as shown by dotted lines in the same figures.

Head operating means

25 Suitable means is provided for forcing the press head downwardly to its pressing position against the action of the springs —19— and for this purpose is provided a cam plate —24— having an upwardly and forwardly 30 inclined operating handle or lever —25— rigidly secured thereto for turning the cam plate —24— from a normally flat horizontal position to a substantially vertical position, said plate being interposed between the lower 35 edges of the upper arms —15— of the carriage —3— and upper surface of the press head —4— as shown more clearly in Figures 3, 5, 6 and 8.

40 The thickness of the cam plate —24— between the upper arms —15— of the carriage —3— and upper surface of the press head —4— is somewhat less than the distance between those parts to permit the interposition 45 of a pair of slides —26— between the cam plate and lower edges of the arms —15— and also to permit the interposition of a pressure regulating member —27— between the cam plate and upper surface of the head —4— as shown more clearly in Figures 3 and 6.

50 It will also be observed that the thickness of the cam plate —24— is about equal to the normal distance between the lower edges of the slides —26— and upper surface of the 55 pressure regulating member —27— when the

press head is in its normal elevated position in which position the cam plate will be normally held flatwise between the parts —26— and —27— due to the upward pressure of the front ends of the springs —19— acting upon the press head —4— to elevate the same. 70

75 The opposite ends of the cam plate —24— between the arms —15— and press head —4— are of considerably greater width than the normal distance between the parts —26— and —27— so that when the cam plate is turned from its normal flat horizontal plane to a substantially vertical position the front edges thereof will bear against the undersides of the slides —26— while their rear edges will bear against the upper face of the member —27—, thereby forcing the press head —4— downwardly against the action of the springs —19— into pressing co-action with the buck —2— when the press head is 80 moved into registration with the buck as shown by full lines in Figure 3.

85 During this latter operation the press head engages the work on the buck just before the cam plate reaches its vertical position, thereby placing the upper arms —15— under more or less spring tension while the lower arms —15— are held against undue vertical movement by reason of their engagement with the undersides of the overlying frame bars —11— of the buck-supporting frame —1—. 90

95 That is, when the press head —4— is forced downwardly into pressing co-action with the buck —2— by the turning of the cam plate —24— to a vertical position, downward pressure will be exerted by said cam plate upon the buck through the medium of the head —4— while at the same time upward pressure will be exerted upon the upper arms —15— of the carriage —3— tending to move said carriage vertically but this vertical movement of the carriage is resisted by the engagement of the lower arms —15— with the undersides of the frame members —11— tending to lift the buck-supporting frame, but such tendency is resisted by an equal downward pressure upon the upper surface of the buck, thus permitting the upper arms —15— to be placed under more or less 105 spring tension which is sufficiently high to produce the desired ironing pressure upon the garment. 110

115 Each of the slides —26— is preferably 120 U-shaped in cross section to form a channel for receiving the lower edge of the adjacent upper arm —15— of the carriage —3—, the lower closed side of said slide forming a raceway for anti-friction balls —29— between the bottom of the slide and lower edge 125 of the arms —15— as shown more clearly in Figure 6 to enable the slides to move freely backward and forward along their respective arms —15— by the turning movement of the cam plate —24—. 130

The object of the slides —26— and balls —29— is to reduce friction incidental to the turning operation of the cam plate.

The ends of the channels in the slides —26— are provided with stop flanges —26'— for limiting the endwise movement of the slides, the rear flanges —26'— serving to hold the balls —29— against rearward displacement from their respective slides.

The upper arms —15'— of the carriage —3— are provided in their undersides with pendant stop flanges 29' which serve to hold the balls in the channels against undue forward displacement.

The cam bar —24— extends lengthwise of the machine between and beyond the upper arms —15'— of the carriage —3— and is held against forward and rearward displacement by upright posts —30— which are secured to the top of the press head —4— to extend upwardly therefrom at the outer sides of the upper arms —15'— of said carriage, said posts being arranged in transversely spaced relation across the front and rear edges of the adjacent ends of the cam bar as shown more clearly in Figures 1, 3, 5 and 8.

The front and rear edges of each end of the cam bar —24— are provided with recesses —31— open at the outer edges of the bar for receiving the adjacent posts —30— to hold said cam bar against endwise movement relatively to the press head while permitting free rocking movement of the cam bar from a substantially flat horizontal position to a vertical position and vice versa, as shown more clearly in Figures 5 and 8.

The front edges of the portions of the cam bar —24— directly over the slides —26— are provided with recesses —24'— for receiving pendant flanges —26'— on the undersides of the slides for limiting the rearward movement of the slides across the upper faces of the adjacent portions of the cam bar when the latter is in a flat horizontal position as shown more clearly in Figure 6.

The distance between the inner walls of the recesses —31— of each bar in opposite ends of the cam bar —24— is approximately equal to the distance between the adjacent posts —30— so that when the cam bar is in a flat horizontal position it will be held by the posts against forward and rearward movement except that it is free to rock upwardly and rearwardly from the horizontal position shown by full lines in Figures 3 and 8 to a substantially vertical position as shown by dotted lines in Figure 3.

I preferably employ a pair of similar pressure regulating devices —27—, each of which is located in a horizontal plane between the upper surface of the press head —4— and underside of the adjacent end of the cam bar —24— as shown in Figures 5 and 8, said pressure regulators being rotatably mounted upon the front posts —30— and are each

provided with a plurality of, in this instance five, radial arms —27'— arranged in uniformly spaced relation circumferentially about the axis of their central posts —30— as shown in Figure 5.

The lower faces of these arms —27'— rest flatwise upon the upper surface of the press head —4— but the upper surfaces of the outer ends of the arms —27'— are provided with recesses —33— of different depths so that the adjacent portions of the arms will be of different thicknesses to compensate for different thicknesses of the articles operated upon and also to enable the press head to be forced to its pressing position under different pressures according to the nature of the work by the turning of the cam bar from its horizontal to its vertical position, it being understood that the members —27— may be rotated about their respective posts —30— to successively register the outer ends of their arms —27'— with the inner walls of the recesses —31— in the rear edges of the opposite ends of the cam plate so that when the latter is turned from a horizontal position as shown in Figure 8 to a vertical position as shown by dotted lines in Figure 3, the inner walls of the cam plate will enter the registering notches —33— in the arms —27'—, the lower walls of said notches forming fulcrum bearings upon which the cam plate is turned to effect the desired depression of the press head into pressing co-action with the buck —2—.

The arms —27'— are provided with identification characters such as the numerals 1, 2, 3, 4 and 5 arranged equal distances from the axis of rotation of the member —27— so that the numerals of each member —27'— may be brought one by one into registration with suitable sight openings —34— in overlying portions in opposite ends of the cam plate —34— as shown in Figures 5 and 8.

The cam plate —24— may be provided with ball detents —35— just at the rear of the sight openings —34— adapted to enter recesses —35'— in the registering arms —27'— for frictionally holding the members —27— in their adjusted positions, it being understood that each member —27— may be adjusted by hand angularly about its axis to selectively bring any one of the arms —27'— into registration with the sight openings —34— and incidentally directly under the rear edges of the adjacent portions of the cam plate —24—, for the purpose previously described.

The rearward movement of the carriage —3— is limited by a chain —36— or other suitable limiting device having one end preferably attached to the rear lengthwise bar —11— of the buck-supporting frame and its other end attached to the front cross shaft —16— of the carriage as shown more clearly in Figures 3 and 4, the length of the chain being sufficient to allow the carriage to move 130

from the position shown by full lines to the position shown by dotted lines in Figure 3.

- The bottom plate —5— of the buck —2— is preferably perforated at —40— throughout the major portion of its area to allow any water vapor or water of condensation which may pass into the pad —6— during the ironing operation to escape downwardly through the perforations in the plate —5— and at the same time to allow air to circulate through the perforations for the purpose of keeping the pad —6— in a more or less dry condition.

Operation

- 15 When it is desired to use the ironing press the buck-supporting frame with the buck thereon will be placed in any convenient position upon the surface of a table —8— or other flat support capable of receiving and supporting the buck-supporting unit and head-supporting unit.

20 The head-supporting unit is then placed upon the table in proper position to move transversely of the buck between the opposite end rails —8— of the buck-supporting frame and is then moved to its rearmost position until limited by the stop chain —36—, thereby leaving a clear open space above and around the marginal edges of the buck for the reception of the article to be ironed.

25 After the work has been properly smoothed out upon the upper surface of the buck the carriage is brought forwardly by hand, preferably through the medium of the handle —18— or —25—, until the head —4— is in a position directly over the buck —2—, it being understood that the head has been previously heated, preferably by a self-contained electric heater and that the cam plate —24—

30 will be in its normal flat horizontal position, the head being then yieldingly suspended from the front ends of the springs —15— in vertically spaced relation to the upper surface of the buck.

35 Now, in order to effect the ironing operation, the cam plate —24— will be rocked from its normal horizontal plane to a substantially vertical plane, thereby causing the rear edges of its opposite ends to engage the upper faces of the underlying arms —27— of the pressure-regulating members —27—, while the front edges of the same ends will be brought into engagement with the undersides of the slides —26— which are free to slide rearwardly along the undersides of the upper arms —15— of the carriage, to exert downward pressure upon the press head —4— into pressing co-action with the buck —2— and

40 at the same time to exert upward pressure upon the front ends of the upper arms —15— of the carriage to place said arms under more or less spring tension which is transmitted to the head —4— and thence to

45 the work on the buck through the medium

of the cam plate —24— and pressure-regulating member —27—.

It is, of course, understood that when the cam plate is moved to its vertical position it will automatically lock the press head in its pressing position upon the work, thus permitting the heat of the head to be transmitted to the work for a sufficient length of time to effect the desired ironing operation upon the work.

50 The time required for efficient ironing effect is comparatively small, usually only a few seconds, while at the same time a considerable area of the work corresponding to that of the buck and head will be ironed in one operation.

55 As soon as the ironing operation is completed the cam plate —24— will be restored to its normal horizontal plane by means of the handle —25—, thereby allowing the springs —19— to raise the head clear from the work and also from the buck immediately following which the carriage with the head thereon is returned to its rearmost starting position, either by the handle —25— or handle —18—, thus completing one ironing operation which may be repeated upon different portions of the same article or upon different articles in the manner described.

60 During this pressing operation, or at any time between the operations any vapor or moisture of condensation arising from contact of the heated press head with the moistened articles may pass downwardly through the perforations in the bottom plate of the buck to the atmosphere or, through the same passages, air may circulate to keep the pad of the buck in a more or less dry condition without the aid of any extra air circulating means.

65 When the ironing operations are completed the buck-supporting unit and head-supporting unit may be readily removed together or separately from the surface of the table or other support and laid aside in compact space ready for re-use when necessary.

70 It will be observed that this device is adapted more specifically for household use to take the place of the usual mangle and that by reason of its simplicity and large ironing area 115 it is far more expeditious and efficient in its operation upon the work than a mangle in addition to the fact that it reduces to a minimum the liability of accidents from burning or pressure of the hands or arms between the 120 pressing elements, thereby rendering the machine as a whole extremely desirable for household laundering.

I claim:

75 1. In an ironing press, the combination with a substantially flat horizontal supporting surface, separate frames each movable horizontally to different positions upon said surface and provided with separate pressing elements in different horizontal planes adapt- 125

ed to be moved into and out of vertical alignment by the relative movement of said frames, means operable at will for moving one of the registering elements into pressing coaction with the other element, and co-operative means on said frames for preventing relative vertical movement of the frames during the pressing operation.

2. In an ironing press, a horizontal support, a buck-supporting unit and a head-supporting unit provided with a buck and head respectively, both units being movable to different positions along and upon the support into and out of vertical alignment with each other, means for moving said head vertically into and out of pressing coaction with the aligned buck, and cooperative means on said units for preventing relative vertical movement thereof during the pressing operation.

20 3. In an ironing press, the combination with a substantially flat and horizontal supporting surface, a buck-supporting frame movable to different positions upon said surface and provided with a buck, a wheel carriage movable upon said surface and provided with a press-head movable therewith to and from a position above and in vertical alignment with the buck, and means for moving the press-head into and out of pressing coaction with the buck when registered therewith and cooperative means on the frame and carriage for preventing relative vertical movement thereof during the pressing operation.

25 4. In an ironing press, a substantially horizontal supporting surface, a buck supporting frame provided with a buck and having feet resting upon said surface in movable relation thereto, a head-supporting frame provided with a head and having rollers resting upon said surface to enable the head to be moved to and from a position over the buck, means for forcing the head into pressing co-action with the buck when overlying the same, and co-operative means on said frames for holding the head supporting frame against vertical displacement from said supporting surface during the pressing operation.

30 5. In witness whereof I have hereunto set my hand this 25th day of August, 1930.

FRANK E. BAKER.
